UNITED STATES PATENT OFFICE.

GEORGE K. CUMMINGS, OF NEW YORK, N. Y.

DESIGN FOR A PRISM-WINDOW.

SPECIFICATION forming part of Design No. 33,670, dated December 4, 1900.

Application filed August 15, 1898. Serial No. 688,625. Term of patent 7 years.

To all whom it may concern:

Be it known that I, GEORGE K. CUMMINGS, a citizen of the United States, residing at New York, in the county and State of New York, 5 have invented and produced a new and original Design for Prism-Windows, of which the following is a specification.

My invention relates to a new and original design for prism-windows and is illustrated 10 in the accompanying drawings, in which—

Figure 1 is an elevation or front view of a prism-window embodying my said design, and Fig. 2 is a vertical cross-section through the middle of the window.

15 As shown in the accompanying drawings, my design consists of panes, plates, or lights of parallel prisms represented by the light parallel lines and inclosed within a rectangular parallelogram and separated by a frame-
20 work represented by double lines and ar- ranged as follows: Within the parallelogram at the bottom is a row of rectangular square or approximately square prism-lights. Above said rectangular lights is a row of Gothic-
25 shaped prism-lights with their upper ends pointed or meeting at an angle in Gothic arches. Above these rows of Gothic-shaped lights is another row of kite-shaped prism- lights, the lower angle of said lights resting 30 in the angle between the arches of the Gothic-

shaped lights. Said kite-shaped lights are formed of four sides meeting at four different angles. Next above the kite-shaped lights is a row of triangular-shaped prism-lights with their apices resting within the angle formed 35 by the junction of the side angles of the kite-shaped lights. The various figures or lights above described are of such size and shape that they fit closely against one another, and the upper sides of the kite-shaped lights will 40 be a continuation of the upper or curved sides of the Gothic-shaped lights, giving the appear- 45 ance of Gothic-shaped lights of double the size of those above described and having a vertical divisional line, but with the upper curved lines crossing each other.

The whole Gothic design presents Gothic-like characteristics.

The whole design gives the appearance of a barred or grated prism or lined window. 50

I claim—

The design for a prism-window as herein shown and described.

In testimony whereof I have signed my name to this specification in the presence of 55 two subscribing witnesses.

GEORGE K. CUMMINGS.
